CLAIM

The ornamental design for a medical patch, as shown and described.

DESCRIPTION

FIG. 1 is a front view of a medical patch of the present invention.

FIG. 2 is a rear view of the medical patch of FIG. 1.

FIG. 3 is a top plan view of the medical patch of FIG. 1.

FIG. 4 is a bottom view of the medical patch of FIG. 1.

FIG. 5 is a right side view of the medical patch of FIG. 1.

FIG. 6 is a left side view of the medical patch of FIG. 1.

FIG. 7 is an enlarged 2-2 sectional view of the 1-1 portion of the medical patch of FIG. 1.

FIG. 8 is an enlarged 3-3 sectional view of the 1-1 portion of the medical patch of FIG. 1.

FIG. 9 is an enlarged perspective view of the 4-4 and 5-5 portions having shading on the ragged surface of the medical patch of FIG. 1 showing the embossed surface of the cover sheet.

FIG. 10 is a perspective view of the medical patch of FIG. 1 with the cover sheet partly removed.

FIG. 11 is a bottom view of the medical patch of FIG. 1 with the pull tab raised; and,

FIG. 12 is a bottom view of the medical patch of FIG. 1 with the cover sheet partly removed.

1 Claim, 12 Drawing Sheets
